US00D989443S

(12) United States Design Patent (10) Patent No.: US D989,443 S
Prat (45) Date of Patent: * Jun. 20, 2023

- (54) SHOE
(71) Applicant: GIVENCHY, Paris (FR)
(72) Inventor: Pascal Prat, Paris (FR)
(73) Assignee: GIVENCHY, Paris (FR)
() Term: 15 Years
(21) Appl. No.: 35/512,924
(22) Filed: Oct. 21, 2021

(80) Hague Agreement Data

- Int. Filing Date: Oct. 21, 2021
Int. Reg. No.: DM/217136
Int. Reg. Date: Oct. 21, 2021
Int. Reg. Pub. Date: Nov. 12, 2021
(51) LOC (14) Cl. 02-04
(52) U.S. Cl. D2/908; D2/902; D2/907
